United States Patent Office.

WINFORD R. S. HUNTER, OF BLACKBERRY STATION, ILLINOIS, ASSIGNOR
TO HIMSELF AND H. T. ROCKWELL.

Letters Patent No. 78,876, dated June 16, 1868.

IMPROVED BED-BOTTOM.

The Schedule referred to in these Letters Patent and making part of the same.

TO ALL WHOM IT MAY CONCERN:

Be it known that I, WINFORD R. S. HUNTER, of Blackberry Station, in the county of Kane, and State of Illinois, have invented a new and useful Improvement in Bed-Bottoms; and I do hereby declare and make known that the following is a full, clear, and exact description of the same, reference being had to the accompanying drawings, and the letters and figures marked thereon, which form part of this specification.

My invention relates to that class of removable spring-bed bottoms, in which the mattress or bed is supported upon slats resting upon springs, or rendered elastic by their mode of attachment; and it consists in a novel mode of constructing and arranging the parts, substantially as hereinafter fully set forth.

To enable those skilled in the art to understand how to construct and use my said invention, I will proceed to describe the same with particularity, making reference in so doing to the aforesaid drawings, in which—

Figure 1 represents a plan view of my invention,

Figure 2 is a side view thereof,

Figure 3 is a cross-section, taken at *x* in fig. 2, and

Figure 4 is a cross-section, taken at the line *y* in fig. 2.

Similar letters of reference in the several figures denote the same parts of my said invention.

A represents a cross-sill, whose ends rest upon suitable supports at the centre of the side rails of the bedstead, and form the only point for supporting the bed-bottom.

Upon said cross-sill *A* are arranged, at suitable distances apart, longitudinal slats *B*, there being arranged upon the edges of the cross-sill, and between it and the slats *B*, strips or blocks of rubber, *a a*, as seen in the drawings.

Upon the top of the said longitudinal slats *B*, and directly over the sill *A*, is a bar or slat, *E*, firmly secured and screwed to said sill, so as firmly to hold the slats *B* in place, they being clamped between the sill and the bar *E* by the turning in of the screws.

Upon each end of each of said slats *B*, blocks, *D*, of suitable height are firmly secured by screws, or otherwise, as shown, and upon the top of said blocks *D*, over and parallel with the slats *B*, are other longitudinal slats *C*, upon which the mattress is designed to lie.

These slats *C* are secured to the blocks *D* by means of headed screws, or their equivalent, marked *d*, passing through longitudinal slots *c*, in the ends of the slats *C*, the heads preventing the slats from being separated from the blocks, while the slots *d* permit a longitudinal movement of the blocks, with respect to the slats, as the said slats are pressed down or rise with the weight of the person lying upon the bed, thus giving a free elastic spring to the bed, as desired, which is materially augmented by the action of the springs *a a* beneath the lower slats *B*.

In order to keep the slats *C* in a vertical position, with respect to the lower slats *B*, so as to preserve their elastic force, and not break the ends of the slats from the blocks *D*, I extend a rubber or other elastic strip, *b*, across the bed-bottom, over the centre, each end of said strip being secured to the end of the cross-sill *A*, and the said strip being secured to the slats *C* respectively, as shown, thus retaining the slats *C* in the desired position, and yet fully permitting the vertical yielding and springing of the bed.

Having described the construction of my improvement, I will specify what I claim, and desire to secure by Letters Patent.

I claim the combination of the cross-sill *A*, springs *a a*, slats *B*, blocks *D*, slats *C* with slots *c*, and elastic strap *b*, all arranged in the manner and for the purposes herein set forth and shown.

W. R. S. HUNTER.
